UNITED STATES PATENT OFFICE.

HENRY F. COX, OF ALTOONA, PENNSYLVANIA.

INTERLOCKING LEVER.

SPECIFICATION forming part of Letters Patent No. 255,774, dated April 4, 1882.

Application filed July 8, 1881. (No model.)

To all whom it may concern:

Be it known that I, HENRY F. COX, of Altoona, county of Blair, and State of Pennsylvania, have invented new and useful Improvements in Interlocking Levers; and I do hereby declare that the following is a full and exact description of the same, reference being had to the accompanying drawings, and to the letters of reference marked thereon.

10 This invention consists mainly in certain specific details of construction, fully described hereinafter, by means of which simplicity is obtained without impairing the efficiency of the mechanism in operation.

15 In the drawings, Figure 1 represents a side elevation of my improved lever-stand; Fig. 2, a front elevation of the same; Fig. 3, a plan view of the cap-piece B; Fig. 4, a plan view of the locking-plate C; Fig. 5, a plan view of the 20 locking-plate in position upon the cap-piece; Figs. 8, 9, and 10, similar views, with the levers represented in different positions; and Figs. 6 and 7 represent diagrams illustrating one way of applying my invention in practice.

25 To enable others skilled in the art to make my invention, I will proceed to describe fully the construction and operation of the same.

A, Figs. 1 and 2, represents the body portion of a lever-stand, which may be constructed 30 generally in any proper manner.

B, Figs. 1, 2, and 3, represents a cap-piece supported by the body portion, consisting of a rectangular casting provided with transverse ribs b, Fig. 3, projecting in a vertical plane, 35 and the longitudinal slots b' b'', located on each side of the longitudinal center line, as shown.

C, Figs. 1, 2, and 4, represents what may be termed, for convenience, the "locking-plate," consisting of a rectangular casting, having 40 upon one side of its longitudinal center line a straight-sided slot, c, with a square recess, c', at one end, and upon the other side an inclined-sided slot, c'', as shown.

c' c'' represent elongated openings at the end 45 of the plate, by means of which and proper bolts the locking-plate is fastened to the cap-piece in such manner as to be capable of moving freely in a lateral direction within certain limits.

50 D, Figs. 1, 2, and 8, represents a lever of any proper construction pivoted at the proper point to the body portion, the upper part of

which extends through the longitudinal slots b' c'' in the cap-piece and locking-plate, as shown in Figs. 1 and 8.

E represents also a similar lever, the upper part of which extends through the longitudinal slots b' c'' in the cap-piece and locking-plate, as shown.

F, Fig. 1, represents a curved bar or bars, 60 having at each end a notch or recess adapted to hold the bolt end of the locking-latch f' of the lever in the manner well understood.

When the parts are properly united together and are in their normal position, the lever D is 65 at what may be termed, for convenience, the "front end" of the inclined slot c'' in the locking-plate, and the lever E in the recess c' at the front end of the straight slot, as shown in Fig. 8. The lever E, it will be observed, is then 70 held from movement in a lateral direction by the longitudinal slot in the cap-piece and from movement in a backward direction by the rear sides of the recess c', as shown. When, however, the upper end of the lever D is moved 75 backward from its normal position it gives the locking-plate, by contact with the inclined side of the same, movement in a lateral direction, and by means of this movement the rear side of the recess c' is shifted out of the line of the 80 movement of the lever E, as shown in Fig. 9. In consequence of this change of position the lever is released, so that it may be moved in a rearward direction, if desired, into the position shown in Fig. 10.

85 From the foregoing it will be understood that when the parts are in their normal position the lever E is absolutely locked against movement by the position of the locking-plate C, and that this position can only be changed 90 to release the lever by actuating the lever D. It follows, therefore, that the order of movement of these two levers is absolutely fixed—that is, the lever D must first be moved and then the lever E. This interlocking-lever 95 mechanism is adapted for use in any case when it is essential that certain levers shall be moved in a fixed order.

One of the ways in which my invention has been applied practically will now be described.

100 x, Fig. 6, represents the lever-stand before described.

x' represents a system of rods and cranks, by means of which the pressure of lever D is

conveyed away to a proper distance-point for the purpose of actuating a switch, x^2 , as shown.

x^3 represents a line of connection, by means of which the lever is caused to actuate also a signal, x^4 .

y represents a system of rods and cranks, by means of which the lever E is caused to actuate the signal y' .

The operation is substantially as follows:

- 10 The signal x^4 , when in its normal position, Fig. 6, indicates "safety," and permits consequently the free passage of trains over the track z in the direction of the single arrows in full lines. The switch-signal y' , when in its 15 normal position, indicates "danger," and prevents consequently the passage of trains in the direction of the dotted arrow beyond the switch x^2 . When thus arranged a train moving in the direction of the dotted arrow will 20 be arrested by the signal y' . When, however, it is desired to pass trains over the branch track z' , in the direction indicated by the double arrow, a change must be made, and to insure perfect safety this must be performed in a fixed order. Before the switch-signal y' can be changed 25 from its "danger" position to that of "safety," to permit the movement of a train over the track z' , the signal x^4 must be changed from its "safety" position to "danger," in order to stop the 30 movement of trains over the track z , and the

switch x^2 must also be shifted. By the proper movement of the lever D the signal x^4 is changed from its normal position of "safety" to its "danger" position, and also the switch x^2 is changed. By the movement of lever D also the lever E 35 is unlocked, so that it can be moved. By said movement of lever E, then, the signal y' is changed from "danger" to "safety," to permit the train to pass upon the track z' .

I claim—

1. In combination with the body A, the cap-plate B, having the transverse ribs b b and the straight slots b' b'' , the locking-plate C, having the straight-sided slot c , with recess c' and slot c^2 , with inclined sides and the elongated openings c^3 c^3 , and the levers D and E, as described. 40

2. In combination with the cap-plate B, the locking-plate C, with slots c , c' , and c^2 , and the levers D E, the lines of connection x^4 x^2 , 50 actuating the switch, the line x^3 , actuating the signal x^4 , and the line of connection y , actuating the signal y' , as described.

This specification signed and witnessed this 6th day of July, 1881.

HENRY F. COX.
